(57) **CLAIM**

The ornamental design for a temperature display device support, as shown and described.

DESCRIPTION

FIG. 1 is a bottom perspective view of a temperature display device support showing the present invention;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top plan view thereof; and,
FIG. 7 is a bottom plan view thereof.

The broken lines in the figures show structure or boundaries that form no part of the claimed design, but rather show the environment in which the design is associated, or show portions of the article in which the design is embodied or applied that are not considered part of the claimed design.
